CLAIM

The ornamental design for an intelligent package delivery box, as shown and described.

DESCRIPTION

FIG. 1 is a front, right and top perspective view of an intelligent package delivery box, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged portion view taken from encircled portion labeled, "FIG. 9," in FIG. 1.

The even dashed broken lines in the drawings are included for the purpose of illustrating portions of the intelligent package delivery box that form no part of the claimed

(Continued)

design. In addition, the dot-dash broken lines in the drawings illustrate the boundary lines of the enlarged portion view of FIG. 9.

1 Claim, 9 Drawing Sheets
